US0D1102764S

(12) **United States Design Patent** (10) Patent No.: **US D1,102,764 S**
(45) Date of Patent: ** *Nov. 25, 2025

(54) **CHAIR**

(71) Applicant: **HASKELL OFFICE**, Bala Cynwyd, PA (US)

(72) Inventors: **Bruce Robins**, Philadelphia, PA (US); **John Myers**, Columbus, OH (US); **Erin Leigh Olesen**, Saugatuck, MI (US); **Matthew R Ruster**, Zeeland, MI (US); **Lucas Vinecki**, Hudsonville, MI (US); **Timothy David Stoepker**, Grand Rapids, MI (US); **Lucas Matthew Schupbach**, Paw Paw, MI (US)

(73) Assignee: **HASKELL OFFICE**, Bala Cynwyd, PA (US)

(*) Notice: This patent is subject to a terminal disclaimer.

(**) Term: **15 Years**

(21) Appl. No.: **29/898,485**

(22) Filed: **Jul. 27, 2023**

(51) LOC (15) Cl. **06-01**

(52) U.S. Cl. **D6/336**

CLAIM

The ornamental design for a chair as shown and described.

DESCRIPTION

FIG. 1 is a front perspective view of the chair of the present invention.

FIG. 2 is a right-side view thereof;

FIG. 3 is a front view thereof;

FIG. 4 is a left-side view thereof;

FIG. 5 is a rear view thereof;

FIG. 6 is a top view thereof; and

FIG. 7 is a bottom view thereof.

FIG. 8 is a front perspective view of the present invention shown in an alternate environment.

FIG. 9 is a right-side view of the present invention shown in an alternate environment.

FIG. 10 is a front view of the present invention shown in an alternate environment.

FIG. 11 is a left-side view of the present invention shown in an alternate environment.

FIG. 12 is a rear view of the present invention shown in an alternate environment.

FIG. 13 is a top view of the present invention shown in an alternate environment; and,

FIG. 14 is a bottom view of the present invention shown in an alternate environment.

In the drawings, the broken lines show portions of the chair that form no part of the claimed design.
